UNITED STATES PATENT OFFICE.

JAMES DUVALL, OF CAMAS, WASHINGTON.

DUST AND INSECT PROOF PACKAGE.

Application filed June 14, 1923. Serial No. 645,434.

My invention has for its object the providing of a dust and insect proof package especially adapted for shipping dried raisins and other dried fruits, and to produce such a package inexpensively.

A mere box lined with sheets of paper will not answer, because the sheets would not provide any seal at the corners of the walls of the box, which are the points most 10 vulnerable to both insects and dust.

Likewise, a mere paper bag would not answer as a lining for the box, because the fruit packed in the box is compressed more or less, by means of a plate and press, which 15 would tend to burst the bag unless fitted to the walls of the box and effectively supported thereby throughout its surfaces. Besides those portions of the bag projecting above the wall of the box would interfere 20 with the work of said compression plate.

I attain my object by placing the pack of dried fruit in a container consisting of an outer box of firm material, for example wood, and including a cover, the interior 25 dimensions of said outer box being less than the volume of the pack before its compression as hereinafter mentioned; then placing in said outer box a protective lining bag made of flexible material, said bag 30 being of the same form as the interior of the box but of greater length than the depth of the latter, the upper wall portions of the bag being slitted, said slits terminating at the top of the box thus converting the upper 35 or projecting wall portions of the bag into adjacent flaps, then temporarily compressing the pack to form a marginal depression at the top, then releasing the pack and lapping said flaps one over the other 40 over the pack; then pressing inward upon the pack the unslitted upper portions of the bag body to seal the inner ends of the slits between adjacent flaps, then pressing the cover of the box down on the top of the box 45 and securing it in place whereby the pressure of the pack against the cover holds the flaps firmly in place, and thus maintains said seals.

The details of the construction of my 50 package are illustrated in the figures of the accompanying drawings, in which:—

Fig. 1 represents a lining tube made of paper and slitted at its opposite ends to provide the flaps at the bottom end for 55 sealing that end, and other flaps at the top end, and the creases provided to facilitate

the folding of the lining tube are indicated by dash-and-dot lines;

Fig. 2 represents the bottom end of the lining tube as sealed, and folded so as to arrange the lining tube into a flat package for 60 temporary storage.

Fig. 3 is perspective view of my lining tube set up ready to be inserted in the box which it is to line, with the slitted top portions of the walls of the bag turned outwardly, on the creases *r*;

Fig. 4 is a vertical section taken centrally lengthwise of the box, lined with my lining tube, and filled with fruit ready to be compressed; a rim plate is shown as set on the top of the box through which works the 65 usual follow-plate of the press; and

Fig. 5 is a similar section as Fig. 4 showing the package completed with the cover 70 of the outer box in place, and diagrammatically illustrates the sealing seams formed in the lining of the box along the top of the latter, thus rendering the package 75 dust and insect proof.

Referring now to the reference letters:—

The paper lining tube shown in Fig. 1 is made of a thin flexible paper of close texture the length of the tube is less than its width, due to the interior dimensions of the 80 box for which my tube shall constitute the lining. *s* designates the longitudinal seam of the tube. The lower end of the tube is provided with longitudinal slits *f* and *f'* forming flaps *g*, *g'*, *g''* and *g'''*. The upper 85 end of the tube is provided with slits *h* and *h'* extending lengthwise of the tube relatively to the height of the walls of the box for which the tube shall constitute the lining and so as to provide the flaps *i*, *j*, *k*, 90 *l*; see Fig. 4.

The tube is provided with creases as *m*, *n* to facilitate the arranging and pasting of the bottom flaps and the tube is further provided with the vertical creases *p*, *q*, and the 100 horizontal creases *o*, *r*; the creases *o*, *r*, adapting the bottom end of the tube, when sealed, to be folded flatwise; the creases *o* and *r* must be located at the top of the box in which the bag is to be inserted; the 105 creases *o*, *r*, *p*, *q* facilitate the setting up of the bag, opened out as shown in Fig. 3, when inserted in the box; and the creases *r*, further facilitating the arranging of the flaps *i*, *j*, *k*, *l* outward as shown by Fig. 3.

The lining tube is made of such dimensions that when set up it may be readily

set into the box for which it shall constitute the lining. When inserted in the box the flaps *i*, *j*, *k*, *l*, will be turned outwardly. When so arranged the rim plate *u* may be placed on the top of the box over the turned out flaps; and when so arranged the top of the box will be clear for the inserting of the follow plate *t*, of the press, thereby to compress the fruit pack into a more or less solid mass.

The bottom of the follow-plate *t* is concaved so that in the compression of the pack its upper surface will be rendered convex, and thus induce the automatic operations resulting in said ensealing seams of the lining tube along the top of the box. In short, after said compression of the pack, and the removal of the compression plate *t*, the flaps *i*, *j*, *k*, *l*, of the lining tube are lapped crosswise over each other and the upper surface of the pack; and then the cover, *c*, *v*, of the box is placed on the pack and pressed down so that it may be nailed in place. In the latter operation said seams are formed, for the cover will engage the ends of said flaps and hold them against shifting longitudinally; and in consequence as the top of the pack is depressed a fullness will be produced in those portions of the lining located at the junctures, of the flaps with the body of the lining, hence forming folds in such portions along the top of the box; and such fulled portions are finally mashed down into ensealing seams extending across the inner ends of the slits separating adjacent flaps, and thus closing all crevices at such places and in this way effectively sealing the open end of the lining tube.

Incidentally my method shortens the labor in making the package.

Where a box is merely lined with sheets of paper arranged crosswise it usually takes about four persons for the packing operation.

It not only takes time to place the lining sheets properly in the box, but the sheets must also be held in place. With my improved method of packing one operator could do the same work, and do it much better. This is due to the fact that the lining tube consists of a single unit, and may be readily placed in the box which it is to line, and will stay in place. The only work in arranging the lining tube is to turn its flaps *i*, *j*, *k*, *l*, outward, which position the flaps are adapted to assume due to the creasings *p*, as described.

As already mentioned in packing it is customary to place a cast iron frame or rim plate as *u* on the top of the box, and let the follow plate *t* of the press work through

such rim plate crane as illustrated in Fig. 4. The construction of my lining tube permits its slitted upper ends or flaps to be turned outward thus overlapping the top of the box, and said cast iron frame, or rim plate will hold the flaps in place. If, however, the upper end of the paper lining tube were not slitted as at *h* and *h'*, the use of a rim plate as *u*, would be impossible; and likewise the use of a follow plate as *t*, to compress the fruit, would be practically impossible.

I claim:—

1. A dust and insect proof package comprising an outer box made of firm material and including a cover, and a protective lining bag made of flexible material inserted in said box, said bag being of the same form as the interior of the box but of greater length than the depth of the latter, the upper wall portions of the bag being slitted to provide flaps, the slits terminating at the top of the box, a pack of compressed material, initially of greater volume than the capacity of said box, but compressed to the depth of the latter and to form a marginal depression at the top, the flaps of the bag being folded one over the other over the top of the pack after its said compression, and the unslitted wall portions of the bag projecting above the top of the pack being crushed down into said depression, whereby the inner ends of said slits between the adjacent flaps are sealed, and the pressure of the pack against the cover of the box hold the flaps firmly in place and thus maintains said seals.

2. A dust and insect proof package comprising a rectangular outer box made of firm material and including a cover, and a protective lining-bag made of flexible material inserted in said box, said bag being of the same form as the interior of the box but of greater length than the depth of the latter, the upper wall portions of the bag being slitted to provide flaps, the slits terminating at the top of the box, a pack of compressed material, initially of greater volume than the capacity of said box, but compressed to the depth of the latter and to form depressions at the corners of the top, the flaps of the bag being folded one over the other over the top of the pack after its said compression, and the unslitted wall portions of the bag projecting above the top of the bag being crushed down into said depressions, whereby the inner ends of said slits between the adjacent flaps are sealed, and the pressure of the pack against the cover of the box hold the flaps firmly in place and thus maintains said seals.

JAMES DUVALL.
